UNITED STATES PATENT OFFICE.

WILLIAM H. BAKER, OF CENTRAL FALLS, RHODE ISLAND, AND FREDERIC E. KIP, OF MONTCLAIR, NEW JERSEY.

WEFT-REPLENISHING MECHANISM FOR LOOMS.

SPECIFICATION forming part of Letters Patent No. 692,590, dated February 4, 1902.

Application filed August 2, 1899. Serial No. 725,862. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have jointly invented certain new and useful Improvements in Weft-Replenishing Mechanism for Looms, of which the following is a specification.

10 This invention relates to that class of looms which are provided with automatic devices for supplying them with weft or filling; and the object of the invention is to provide the loom with a simple means for supplying a 15 filled weft-carrier to the shuttle in play and to displace the empty or nearly empty weft-carrier in the shuttle whenever the weft-carrier in the latter shall be nearly denuded.

In the accompanying drawings, which illustrate an embodiment of the invention, Figure 1 is a sectional side elevation of a part of a loom, showing this invention applied thereto; and Fig. 2 is an end view of the magazine, showing the rotating devices thereof. Fig. 3 is a front view of the parts seen in Fig. 1; and Fig. 3^a shows the same parts that are seen in Figs. 1 and 3, but representing them as in the act of supplying a filled weft-carrier to a shuttle. Fig. 4 is a sectional plan of the parts seen in Figs. 1 and 3 and illustrating the automatic shuttle - evener. Fig. 5 illustrates another form of magazine adapted to be employed with the invention. Figs. 6, 7, and 8 illustrate the weft-carrier and shuttle on a larger scale than the principal views. Fig. 6 is a fragmentary perspective view of the shuttle and bobbin-holder. Fig. 7 is a plan of the shuttle, the bobbin therein, and the shuttle-box; and Fig. 8 is a longitudinal vertical axial 40 section of the shuttle and bobbin.

In the construction herein illustrated the filled weft-carriers or bobbins are in a suitable magazine, which discharges one bobbin at a time into a receiver, which is situated directly over the shuttle in the shuttle-box on the lay when the vibrating lay has beaten up.

A vibratable knocker on the loom-frame is adapted when actuated by a going part of the loom—as the lay, for example—to drive the 45 full bobbin from the receiver down into the

shuttle and to displace and drive out the denuded bobbin therefrom.

To effect the above object, an electromagnet is adapted to put into position a tappet, which may be a hinged arm carrying the armature of said magnet, which tappet as the lay beats up will actuate said knocker and shift or change the bobbins. The exhaustion of the weft on the bobbin in the shuttle serves to permit the closure of a break in an electric circuit, including the electromagnet, and thus excite the latter.

Referring to the principal views of the drawings, 1 represents the loom-frame generally, and 2 the breast-beam, forming a special part of said frame. 3 is the lay; 4, one of the lay-swords; 5, the swing-rail, about which the lay vibrates, and 6 is the picker-stick at that side of the loom shown in the principal views. All of these parts may be constructed and operated in substantially the ordinary way.

Figs. 1 to 4 show a construction employing an intermittently-rotatable magazine for supplying weft-carriers, and this construction will be first described.

M represents the magazine as a whole, and it consists of a drum 7, fixed on a shaft 8, which rotates in bearings in suitable brackets 9 on the loom-frame. This drum has in its periphery a plurality of cells or pockets 10 to 80 receive the bobbins b. To keep the bobbins from falling out of the pockets, there will be some sort of fixed casing or shield 11, partly inclosing the rotary drum 7. The drum is designed to rotate in the direction of the arrow seen in Fig. 3^a, and there is a bobbin-outlet at the front lower part of the casing or shield to permit a bobbin to roll out from the coincident cell 10 into a receiver 12, under which the shuttle-box 13 on the lay comes whenever the lay beats up. The bobbins b fit quite loosely in the pockets 10, so that they may fall out freely by gravity into the receiver 12; but the receiver, which is in the nature of a hopper open at both bottom and top, has yielding spring nippers or plates 14 at its respective ends, (seen best in Fig. 3,) which embrace the bobbin endwise and hold it with sufficient firmness to prevent it from falling through or out of the receiver by 90 95 100

gravity. Normally there will be a bobbin in the receiver, as seen in Fig. 1.

In a suitable bracket 15 on the loom-frame is mounted a vibrating knocker 16, the head 5 of which is normally situated just above the bobbin in the receiver, as seen in Fig. 1. This knocker has a pendent arm 17, the purpose of which will be next explained, and a suitable retracting-spring 18.

10 Mounted on a bracket 19 on the lay is an electromagnet 20, and also mounted on the lay is a hinged tappet-arm 21, which carries the armature 22 of the magnet. Normally the arm 21 rests on a support 19^a, and it may be 15 held down by a light spring 23, as seen in Fig. 1, in which case when the lay beats up to the position seen in Fig. 1 the end of the hinged tappet-arm 21 will pass under or miss the pendent arm 17 of the knocker 16; but if the 20 magnet 20 be excited and attract its armature 22 the tappet-arm will be lifted, and on the lay beating up it will strike the arm 17. This will cause the knocker 16 to descend suddenly and drive the bobbin *b* in the receiver 25 down into the shuttle *s* in the shuttle-box 13 on the lay. The shuttle is open at top and bottom, and there is also an opening *o* through the lay, so that the entry of the full bobbin from above drives the denuded bobbin 30 *b*^x in Fig. 3^a out of the shuttle, whence it falls down into any suitable receptacle 24 on the loom-frame below.

Before explaining the construction of the shuttle and bobbins and the electrical connections it may be well to state that the construction shown in Fig. 5 is the same, substantially, as that above described, except that the magazine *M*^x is simply an upright non-rotative holder in which the bobbins are 35 superposed, the bottom bobbin being forced out by gravity into the receiver 12.

Figs. 6, 7, and 8 illustrate the construction of the bobbin and shuttle and the electrical construction. The bobbin (indicated by *b* as a whole) comprises a spindle *b*^x, which carries the weft *w*. Around the butt of the bobbin-spindle are fitted one or more (preferably two) metal bands 25, and in its end is a ring or butt-plate, of metal, 26. On the spindle 45 is a ring or piece of metal 27, which is connected electrically with the end plate 26 by a conductor 28 of any kind. Within a slot in the bobbin-spindle is a spring-contact 29, which is secured to or electrically connected 50 with the band or bands 25. The free end of this contact 29 tends by the resiliency of the part to spring outward into contact with the inner face of the ring or piece 27 where the latter bridges the slot; but it is held out of 55 contact by the overwrapped weft on the bobbin-spindle, as seen in Fig. 8.

In the shuttle *s*, and perhaps best seen in Fig. 6, are two spring-plates, of metal, 30 30, which are preferably formed by bending the 60 thin metal into a U shape and securing the same to the shuttle by a screw 30^a. (Seen in Fig. 8.) These spring-plates elastically em-

brace the butt of the bobbin when the latter is forced down into the shuttle and hold it quite firmly, and they contact electrically 70 with the bands or metallic parts 25 on the bobbin. On the shuttle is also secured a spring-plate 31, which when the bobbin is pressed down into the shuttle comes into contact with the butt-plate or ring 26 on the bobbin. 75

The shuttle has on its outer face two contact-plates, of metal, 32 and 32^x, which are connected electrically with the respective spring-plates 30 and 31 by suitable conductors 33 and 34. Thus a current may flow when 80 the bobbin is denuded, or nearly so, from the plate 32 by conductor 33 to plate 31, thence to butt-plate 26, and thence by conductor 28 to the ring or piece 27. The spring 29 being now in contact with ring 27, the current will 85 flow through said spring to the band or bands 25, thence to the spring-plates 30, and thence by way of conductor 34 to the contact-plate 33^x. When the shuttle enters the shuttle-box 13, Fig. 7, the contact-plates 32 and 32^x 90 thereon will come into electrical contact, respectively, with spring-terminals 35 and 35^x on the box. These latter form terminals of an outer operating-circuit formed of conductors *c* and *c*^x and includes the electromagnet 95 20 and any generator *G*. It will be obvious that the moment the exhausted bobbin is driven out of the shuttle the operating-circuit will be broken, and the spring 18 will retract the knocker 16 as soon as the way is clear. 100 On this upward receding movement of the knocker the rotary magazine-drum 7 will be turned thereby to the extent of one cell 10. Any known means for effecting this may be employed. The one herein shown is best illustrated in Fig. 2, which is a view of the end of the magazine seen at the left in Fig. 3. On the shaft 8 is secured a disk or plate 18^x, having as many teeth on its periphery as there are cells 10, and on the bracket 16^x on the 110 knocker 16 is pivotally mounted a beveled spring-latch 16^a, which is adapted to engage the teeth on the disk 18^x. When the knocker 16 is driven down, the latch or pawl 16^a takes under a tooth on the disk, and on the upward 115 receding movement of the knocker the drum 7 is thereby rotated. To steady the drum when rotated and set, a yielding detent 35^a on the casing 11 is so placed as to wipe over and engage a tooth on the disk 18^x. This 120 means for rotating the drum 7 is in the nature of a pawl-and-ratchet device.

When a shuttle *s* enters the shuttle-box 13, it is important that it should always reach and occupy therein a certain position, so that 125 the entering bobbin *b* may make proper contact at its butt through the plate 26 thereon with the spring-plate 31, Figs. 7 and 8, on the shuttle, and to insure this contact a precautionary device is employed, which is best seen 130 in Fig. 4. This device, which we have called the "shuttle-evener," comprises an arm 36, pivotally mounted on the breast-beam 2, so as to have some lateral play, and furnished

with a retracting-spring 37 and a stud or other projecting part 38 on its lower face. This arm 36 projects toward the lay 3 and is placed at such a level that when the lay beats up the free end of the arm projects over the raceway on the lay and lies in the same horizontal plane as the shuttle's in the box. The lay carries a cam-piece 39, which projects toward the breast-beam and has an inclined lateral edge, which as the lay beats up engages the stud 38 and swings the evening-arm 36 to the position seen in Fig. 4. The arm strikes the shuttle and drives it into the shuttle-box to the proper or desired extent. To insure the proper working of this device, the loom should be so constructed that normally when at rest in the box the shuttle will not be quite so far in the box as is desired for the reception of the bobbin *b*. In Fig. 4, *R* represents the reed.

The end of the weft-thread on each bobbin in the magazine will be led therefrom and attached to some point—as, for example, to the pin or holder 40 on a branch from the bracket 9, supporting the magazine, as seen in Fig. 3—and when the shuttle is picked the thread will be drawn automatically into a thread-eye 41 in the shuttle. (Seen in Figs. 7 and 8.)

By the word "bobbin" as herein used is meant any sort of weft-carrier designed to go into a shuttle.

We do not limit ourselves to the specific construction of the mechanisms herein shown, as we are well aware that these may be varied to a considerable extent without departing materially from our invention. For example, the tappet-arm 21, as herein shown, moves or shifts in a vertical direction; but it may as well move horizontally.

We do not herein claim, broadly, in a weft-supplying mechanism a vibrating knocker for driving a bobbin-carrying weft down into a shuttle on the lay, as that has been done by mechanism controlled by the ordinary weft fork and hammer; but this mechanism of necessity acts only when the bobbin is wholly denuded of weft, and therefore leaves a defect in the piece being woven. Our device is controlled electrically, and a full bobbin is supplied before the bobbin in the shuttle is wholly denuded, so that no defect is produced in the piece.

Having thus described our invention, we claim—

1. In a loom, the combination with the vibrating lay, and the shuttle-box mounted thereon, of a rotatable bobbin-magazine, a receiver at the outlet of said magazine, to receive a bobbin delivered therefrom, a vibratable knocker for knocking the bobbin from the receiver down into the shuttle on the lay, mechanism for vibrating said knocker at proper times, electrical means controlling said

knocker-operating mechanism, and means for imparting intermittent rotary impulses to said magazine.

2. In a loom, the combination with the vibrating lay, the shuttle-box thereon, the magazine, and the receiver, situated over the shuttle-box when the lay is at the beating-up point, of the pivotally-mounted knocker, having a pendent arm 17, the retracting-spring 18, the electromagnet on the lay, its armature, the hinged tappet on the lay and carrying said armature, said tappet being so mounted that when the magnet is excited the tappet is alined with the arm on the knocker, the controlling electric circuit, including said magnet and having terminals at the shuttle-box, the shuttle having in it an electric circuit closed with the exterior circuit when the shuttle is in the box, and a bobbin, having in it a circuit closed with that in the shuttle when the bobbin is in place therein, said circuit in the bobbin having in it a self-closing break held open by the weft thereon.

3. In a loom, the combination with the vibrating lay, the bobbin-magazine, the vibrating knocker, the electromagnet, the tappet for actuating the knocker controlled by said magnet, and the outer circuit including said magnet and having terminals at the shuttle-box, of the shuttle, having contact-plates 32 and 32^X to contact with the terminals on the box, the end spring 31 and side springs 30, connected electrically with the respective plates 32 and 32^X, the bobbin, having a metal band or bands 25, which are embraced by the side springs 30, and a metal end piece 26, which is in contact with the end spring 31, the metal ring or piece 27, and the spring-terminal 29, in electric contact with the bands 25, and held out of contact with the piece 27 by the overwrapped weft.

4. In a loom, the combination with a shuttle having two metal contact-plates, a metal plate 31, jaws 30, and conductors connecting said plate and jaws, respectively, with said contact-plates, of a supporting device for the weft, comprising a spindle carrying a contact-piece in metallic contact with the plate 31, a headpiece on said spindle, a metal band or ring on said headpiece and in electrical contact with the jaws in the shuttle, and a spring-contact indicator connected electrically with the contact on the spindle and occupying a slot in the headpiece under the band thereon.

In witness whereof we have hereunto signed our names, this 14th day of June, 1899, in the presence of two subscribing witnesses.

WILLIAM H. BAKER.
